CLAY CUTTING DEVICE

Ernst Frey, Chur, Switzerland

Application March 7, 1935, Serial No. 9,756
In Switzerland October 6, 1934

15 Claims. (Cl. 25—108)

My invention relates to clay cutters and more especially to an automatic clay cutting device adapted for combination and cooperation with a press extruding the clay under the form of a skein. As a rule devices of this kind are provided with wires serving to cut through the skein of clay to divide off prismatic blanks adapted to be converted into bricks by burning and in the particular kind of devices here in view the cutting wires, after having cut through the skein, must be returned to their initial position for a new cutting operation.

In cutting devices of this kind the cutting wires must be stopped after having cut through the skein, in order to allow the blanks to be removed first, before the wires can be returned into their operative position.

It is an object of my invention to provide means whereby the unsatisfactory stopping of the cutting wires can be avoided, the device being formed, in a known manner, as a carriage having a plurality of cutting wires mounted thereon and being moved by separate driving means at a velocity corresponding to the velocity of feed of the skein.

In accordance with the present invention I avoid the necessity of stopping the cutting wires before removal of the cut of blanks by displacing part or all of the wires as well as the supports for the blanks in the direction of feed in such manner that the wires can be returned to their operative position between the blanks after these latter have been spaced from each other.

In the drawings affixed to this specification and forming part thereof an embodiment of my invention is illustrated diagrammatically by way of example.

In the drawings,

Fig. 1 is an elevation,

Fig. 2 a plan view,

Fig. 3 an end view, partly in vertical section,

Figs. 4 and 5 are a vertical cross section and plan view, respectively, of the wire holders, drawn to a larger scale, and

Figs. 6 and 7 are cross sections of the supports of two individual wires.

Fig. 8 is a perspective view of some blank supporting plates together with the mechanism for displacing same.

Fig. 9 is a cross section illustrating a detail of the driving mechanism.

Fig. 10 is a part elevation of a modification in which five cutting wires, instead of only four as shown in Figs. 1 to 9, are provided.

Fig. 11 is a diagram illustrating the sequence of operations which the device shown in Figs. 1 to 9 is going through during each cycle.

Referring to the drawings and first to Figs. 1 to 9, 1 and 2 are the side frames supporting the carriage, these frames being rigidly connected by cross bars 3. 4 is the carriage carrying the cutters, this carriage being supported on the frames 1 and 2 by means of rollers 5. Two cross beams 7 extending in contact with the bottom of the carriage support guide bars 6, the upper ends of which are connected by a frame 1a. 8, 8 are two cutter beams formed with sleeves 8a embracing the guide bars 6 for vertical reciprocation thereon, one such cutter bar being positioned on each side of the skein 9 of clay and of the carriage. On these two cutters bars the cutting wires are mounted, their ends being fixed to holders illustrated in detail in Figs. 4 to 7. 10 is the cylindrical part of a holder, which extends through a boring of one of the cutter bars 8 and is formed at its outer end with an angle 11; in the free arm of which is secured a swivel 12 for stretching the wire. 13 is another angular member fixed to the holder substantially at right angles to the member 11 and serving as a means for rocking the holder through a predetermined angle, as will be explained in detail further below. The inner end of the cylindrical part of the holder carries a U-shaped member 14. Four such holders are here located in each cutter bar 8 and the cutting wires 15 extend across the carriage from one swivel 12 and member 14 to the corresponding members of the corresponding holder mounted in the cutter bar on the other side of the carriage, the wires extending through central bittings of the cylindrical parts 10 and eccentrically across the depending arms 14' of the members 14, which are formed with notches 80. In view of this arrangement of the wires their operative portions, which extend across the carriage and serve for cutting off the blanks, are located eccentrically to the axis of the cylindrical portions 10 of their holders and consequently, if the holders are rocked in the cutter bars 8, the cutting wires will execute an angular movement, whereby they will change their position relative to the plane through which they had been moved when cutting off a blank. As shown in Figs. 6 and 7, the eccentricity of the outermost wire holders 14a and 14d (Fig. 1) is greater than in the inner wire holders 14b and 14c. This is also shown in Fig. 4, where the wire 15 drawn in full lines illustrates the position of the wires held in the holders 14b and 14c, while the wire drawn in dot and dash and 14d, while the wire drawn in dot and dash 55

lines illustrates the position of the wires held by the holders 14a and 14d.

The angular members or checks 13 of the holders 14a and 14b extend to the left, those of the holders 14c and 14d to the right (Fig. 1). Bows 16 for rocking the holders are mounted below and above the carriage, the top bows being fixed in the frame 7a, the bottom bows in the cross beams 7b. The ends 17 of the bows extend into the path of the angular members or checks 13 of the holders and will cause them to rock one way or the other, when the cutter bars 8 are moved vertically one way or the other.

The free end of the skein of clay and the blanks cutting off this skein are supported on plates 18 to 22. The supporting plates 20 and 22 are fixedly mounted on the carriage 4; the supporting plates 18, 19 and 21 are movably secured thereto. 19a is an angular piece connecting plate 19 to a movable rail 23 (Fig. 8), 21a is another angle piece connecting plate 21 to another rail 24. The two rails are supported in U-shaped guide pieces 25 mounted laterally on the carriage 4. One end of each rail 23, 24 is acted upon by compression springs 26, the other end by pins 27 which are acted upon by a rock plate 28 carrying a pin 30 which extends into a notch 29 of the movable supporting plate 18. The rock plate 28 is fixed to a horizontal shaft 31 carrying a lever arm 32, the free end of which is connected by means of a link 33 to the lever arm 34 mounted on a rock shaft 35 which extends across the machine frame and the free end of which carries another lever arm 36 which is connected by a rod 37 to the arm 38 of the main shaft 39, which rotates in the direction of the arrow 52. On the rock shaft 35 are further mounted two arms 40 (Fig. 1), each of which is connected by a link 41 to one of the two cutter bars 8.

40 The arm 34 is mounted on the shaft 35 between a fixed flange 43 and an adjustable ring 42 (Fig. 9), being held between these two members with a certain friction, which causes it to follow the angular movements of the shaft 35, until it 45 meets one of the stops 44 and 45. Thus the lever arm 34 can move only between these two stops, no matter what angle the shaft 35 is rocked through by the main shaft 39, crank arm 38, connecting rod 37 and arm 36.

50 The carriage is moved by a cam 46 fixed to the main shaft 39, the arm 48 of a double-armed lever 48, 49 carrying a roller 47 in contact with the cam 46, while the free end of the lever arm 49 is connected with the carriage by a link 50. 55 One end of the carriage is acted upon by a tension spring 51, which tends to return the carriage to its position of rest and at the same time causes the roller 47 to apply itself to the cam 46. The skein 9 of clay, which is extruded from the press (not shown) moves in the direction of the arrow 53. It is supported by the belt conveyer 54 which controls by means of the belt 55 the friction coupling 56 driven by a belt 57 in such manner, that the main shaft 39 of the cutting device is 60 rotated, in synchronism with the feed of the skein of clay, with an additional force supplied to it by way of the friction coupling 56. This coupling is thus instrumental in permanently adapting the number of revolutions of the main shaft to the velocity of feed, at the time being, 65 of the skein of clay.

This latter, after having passed over the conveyer belt 54, is oiled by means of an oil cylinder 70 mounted in the stationary supporting plate 75 22 and is then fed to the cutting device.

The operation of this device is as follows:

Whenever the skein of clay has been fed forward onto the displaceable supporting plate 18 by a distance equal to the width of a blank, the roller 47 of the lever 48, 49 is forced downwardly 5 by an ascending portion of the cam 46 and the cutter carriage is now moved forwardly in synchronism with the clay feed. At the same time the cutter bars 8 are moved downwardly together with the cutting wires, cutting through the clay 10 and dividing off four blanks A, B, C, and D. Having cut through the skein of clay they are moved on until they have reached their lowermost position. During this movement the angular members or checks 13 of the wire holders 15 14 have met the upwardly projecting ends 17 of the bows 16 mounted below the carriage and the wire holders have been rocked thereby through different angles. The wire holders 14a which direct their wire below the joint between the 20 blanks C and D are turned clockwise and inwardly. The wire holders 14b are turned in the same sense, however here, owing to the smaller eccentricity of the wire, this latter is rocked through a smaller angle. The wire holders 14c, which are 25 carried below the joint between the blanks A and B, is rocked anticlockwise, the member 13 being here directed to the right and consequently the wire mounted on these holders is also rocked to the right. A similar movement is imparted to the 30 wire holders 14d, however in view of the greater eccentricity of the wire mounted thereon this wire is rocked through a greater angle.

In this manner the cutting wires are displaced relative to their cutting planes and are at the 35 same time spaced farther from each other. This angular movement of the cutting wires is imparted to them during the latter part of the downward movement of the cutter bars 8. As soon as the cutter bars start rising again from 40 their lowermost position, the movable supporting plates 18, 19 and 21 are displaced simultaneously in horizontal direction by means of the lever 34 which moves from its uppermost position, in contact with the stop 44, to its lowermost position, in contact with the stop 45. While the other parts including the shaft 35 continue in their angular movement, the lever 34 being arrested by the stop 45 will glide on the shaft 35 45 under friction. During this angular movement 50 of lever 34 towards stop 45 the plate 28 has been rocked from the position shown in Fig. 1 into a position, where its pin 30 has moved the supporting plate 18 towards the left, while at the same time the two pins 27 cause the rail 23 to be 55 shifted to the left, rail 24 to the right, whereby the supporting plate 21 has been shifted to the right, plate 19 to the left. Since the supporting plate 20 fixed to the carriage 4 has not changed its position, the plates 19 and 21 have been spaced 60 from plate 20 and plate 18 from plate 19, gaps having been formed between the plates and the blanks supported thereon, which allow the cutting wires 15 to pass freely between the plates and blanks when being returned into their operating 65 position.

Before the cutting wires start on this return movement, the movement of the carriage 4 is accelerated by the slightly ascending surface of cam 46, whereby a gap is formed between the 70 leading end of the skein of clay and the still unseparated group of blanks. Before the wires enter the gaps between the blanks, the feed movement of the carriage has become equal again to that of the skein of clay.

As soon as the cutting wires have passed through between the blanks and skein, the carriage starts on its return movement, being acted upon by the tension springs 51, since now the 5 roller 47 has reached the descending part of the cam 46. During this time the skein is fed through the length of four groups of blanks and the blanks just cut off are shifted to the left by the skein to be conveyed further by a conveying device 10 (not shown).

In the meantime the cutting wires have passed through their uppermost position, after having been set to their operative positions by the ends 17 of the top bows 16 meeting their check members 13. Directly thereafter the supporting plates 18, 19 and 21 are also returned into their normal positions by an angular movement of shaft 35 in the opposite direction and by the upwardly directed movement of the link 33, so that all the 20 parts are in position for another cutting operation.

In the modification illustrated in Fig. 10 an odd number of cutting wires (five) 58, 59, 60, 61 and 62 is provided, so that here five blanks E, F, 25 G, H, J are cut off, the supporting plates being marked 63, 64, 65, 66. Here the middle wire 60 and the two supporting plates 64 and 65 adjoining it may be stationary relative to the carriage. Since gaps are formed on either sides of 30 the blanks F and G, the wire 60 entering from below into the joint between the blanks F and G is capable of slightly displacing these blanks on their stationary plates 64 and 65, respectively, to the extent of being able to freely rise between 35 them.

As shown in the diagram of Fig. 11, the sequence of the several operations of a cycle is the following:

a illustrates the starting of the cutting operation, i. e. the moment at which the cutting wires 40 come in contact with the skein of clay.

a—b illustrates the period of time, during which the wires cut through the clay, while at the same time the carriage is fed forwards in accordance 45 with the velocity of the skein of clay at the time being.

b marks the moment at which the cutting wires emerge from the clay.

c—d illustrates the period of time during which 50 the wires are imparted their angular movement, being at the same time spaced from each other.

d marks the lowermost position of the cutting wires and the moment when they enter on their return movement.

55 d—e marks the period of time during which the supporting plates are displaced horizontally, whereby these plates as well as the several blanks of the group of blanks are spaced increasingly from each other.

60 c—e illustrates the period of time during which the carriage leads about 6 millimetres relative to the skein of clay in order to provide room for the formation of gaps between the blanks, which starts at d.

65 f—g illustrates the period of time during which the cutting wires return through the gaps between the blanks. During this time the carriage is fed with the same velocity as the skein of clay.

At g the carriage starts on its return movement 70 into the initial position, this movement coming to an end at a.

From h to i the cutting wires are rocked back into their operative positions.

75 At i the wires have reached their uppermost

position, the carriage still continuing its return movement.

From i to k the supporting plates are returned into their initial position.

At a the carriage is once more started on its feed movement and a new cutting operation is initiated, the wires having already been carried into contact with the top edge of the skein of clay.

I wish it to be understood that I do not desire 10 to be limited to the exact details of construction shown and described for obvious modifications will occur to a person skilled in the art.

In the claims affixed to this specification no selection of any particular modification of the 15 invention is intended to the exclusion of other modifications thereof and the right to subsequently make claim in the present application to any modification not covered by these claims is expressly reserved. 20

I claim:—

1. Automatic clay cutting device comprising in combination, clay feeding means, a carriage, a plurality of cutters arranged for reciprocation at substantially right angles to said carriage and 25 automatically operative means for angularly displacing part of said cutters between two cutting operations in the direction of feed.

2. Automatic clay cutting device comprising in combination, clay feeding means, a carriage, a plurality of cutters arranged for reciprocation at substantially right angles to said carriage, clay supports, and automatically operative means for angularly displacing part of said cutters and 30 said supports between two cutting operations in 35 the direction of feed.

3. Automatic clay cutting device comprising in combination, clay feeding means, a carriage, means for moving said carriage in the direction of feed, a plurality of cutters arranged for reciprocation at substantially right angles to said carriage and automatically operative means for angularly displacing part of said cutters between 40 two cutting operations in the direction of feed.

4. Automatic clay cutting device comprising in combination, clay feeding means, a carriage, a plurality of cutters arranged for reciprocation at substantially right angles to said carriage and automatically operative means for angularly displacing part of said cutters through different 45 distances between two cutting operations in the direction of feed. 50

5. Automatic clay cutting device comprising in combination, clay feeding means, a carriage, a plurality of cutters arranged for reciprocation at substantially right angles to said carriage, clay supports, and automatically operative means for angularly displacing part of said cutters and 55 said supports through different distances between two cutting operations in the direction of feed. 60

6. Automatic clay cutting device comprising in combination, clay feeding means, a carriage, a pair of cutting beams arranged for reciprocation at substantially right angles to said carriage, 65 a plurality of cutter holders secured in each beam for rocking motion about their axes, a cutter fixed eccentrically to each holder and automatically operative means for rocking said holders to move part of said cutters in the direction 70 of feed.

7. Automatic clay cutting device comprising in combination, clay feeding means, a carriage, a pair of cutting beams arranged for reciprocation at substantially right angles to said carriage, 75

- 5 a plurality of cutter holders secured in each beam for rocking motion about their axes, cutters fixed to said holders and spaced differently from the axes of their holders, and automatically operative means for rocking said holders to move part of said cutters in the direction of feed.
8. Automatic clay cutting device comprising in combination, clay feeding means, a carriage, a pair of cutting beams arranged for reciprocation 10 at substantially right angles to said carriage, a plurality of cutter holders secured in each beam for rocking motion about their axes, cutters fixed to said holders and spaced differently from the axes of their holders, and automatically operative means including two stops for rocking said 15 holders to move part of said cutters in the direction of feed and vice versa.
9. Automatic clay cutting device comprising in combination, clay feeding means, a carriage, a plurality of cutters arranged for reciprocation 20 at substantially right angles to said carriage, clay supports, automatically operative means for angularly displacing part of said cutters and said supports between two cutting operations in the direction of feed, and additional stationary clay supports.
10. Automatic clay cutting device comprising in combination, clay feeding means, a carriage, a plurality of cutters arranged for reciprocation 25 at substantially right angles to said carriage, clay supports and automatically operative means comprising a friction-operated lever for angularly displacing part of said cutters and said supports between two cutting operations in the direction of feed.
11. Automatic clay cutting device comprising in combination, a carriage, clay blank supporting means, a plurality of cutters and means for displacing said cutters and part of said clay blank supporting means after a cutting operation relative to said carriage so that the cut-off blanks will be spaced from each other and the cutters rendered free to rise in the gaps separating the blanks.
12. Automatic clay cutting device comprising in combination, a carriage, clay blank supporting means, a plurality of cutters, cutter holders, means for angularly moving part of said cutter holders in the direction of feed between two cutting operations and means for displacing said clay blank supporting means after a cutting operation relative to said carriage so that the cut-off blanks will be spaced from each other and the cutters rendered free to rise in the gaps separating the blanks. 5
13. Automatic clay cutting device comprising in combination, a carriage, clay blank supporting means, a plurality of cutters, cutter holders, means for angularly moving part of said cutter 15 holders through different distances in the direction of feed between two cutting operations and means for displacing said clay blank supporting means after a cutting operation relative to said carriage so that the cut-off blanks will be spaced from each other and the cutters rendered free to rise in the gaps separating the blanks. 20
14. Automatic clay cutting device comprising in combination, a carriage, clay blank supporting means, a plurality of cutters, means for displacing said cutters and part of said clay blank supporting means after a cutting operation relative to said carriage so that the cut-off blanks will be spaced from each other and the cutters rendered free to rise in the gaps separating the blanks. 25
15. Automatic clay cutting device comprising in combination, a carriage, clay blank supporting means, an uneven number of cutters and means for displacing said cutters and part of said clay blank supporting means save the middle cutter after a cutting operation relative to said carriage so that the cut-off blanks will be spaced from each other and the cutters rendered free to rise in the gaps separating the blanks. 30
